TRACK TORPEDO AND METHOD OF
MAKING THE SAME

Hugh Williamson Kelly, Woodbridge, N. J.

Application January 7, 1932. Serial No. 585,318

5 Claims. (Cl. 246—487)

This invention relates to improvements in track torpedoes and methods of making the same, the principal object being to provide a novelly constructed torpedo and a simple and efficient method of making the same in large quantities at low production cost.

The improved torpedo of the invention comprises essentially a container for the detonating material, such container comprising a pair of open end telescopic sections, and a flexible strip or strips attached to the container and serving to fasten the torpedo to the head of a railway track or the like.

The method proposed by the present invention comprises the provision of a plurality of containers as described briefly above, the inner or receptacle sections of such containers being of such dimension that they will hold the exact quantity of detonating material required for a charge when filled. The method further comprises the placing of a plurality of the said inner sections in vertically disposed position and in juxtaposed relation to each other, preferably in a shallow box-like tray, so as to completely fill the same and maintain the juxtaposed sections in the desired upright position. The detonating material, which takes the form of a powder, is then introduced into the upright receptacle sections simultaneously until they are filled, the filling operation being carried out by any suitable means which will spray or similarly introduce the detonating material into all of the receptacle sections at the same time. The filled sections are then removed from the shallow tray and the outer or cover sections of the containers are telescopically applied to close and seal the container of each torpedo.

The novel features of construction of the improved torpedo, as well as the method of making it, are more clearly set forth hereinafter in the detailed description of the invention, as illustrated on the accompanying drawing. In the drawing:

Fig. 1 is an exploded perspective view of the telescopic container of one form of the torpedo;

Fig. 2 is a perspective view of the container in closed condition;

Fig. 3 is a perspective view of the container disposed in proper relation to its flexible attaching strip and the strap for attaching these elements together;

Fig. 4 is a perspective view of the completed torpedo;

Fig. 5 is an exploded perspective view of a modified form of torpedo; and

Figs. 6 and 7 present a plan and an elevational view, respectively, of the shallow tray hereinbefore mentioned, which is preferably used to carry out the proposed method, the views illustrating clearly the manner of positioning the receptacle sections of the containers in the tray.

Referring to Figs. 1 to 4 of the drawing, there is disclosed therein one embodiment of the track torpedo of the invention. As shown clearly in Fig. 1, the container, which forms the body of the torpedo, takes the form of a telescopic container comprising an inner or receptacle section 1 and an outer or cover section 2. Each of these sections is formed with a closed and an open end. They may be formed of any suitable material such as those in common use in the making of such torpedoes, a heavy or tough paper preferably being used for this purpose. In accordance with the invention, section 1 is of such dimension that it will hold the exact quantity of detonating material to constitute a charge. In the illustration of Fig. 1, a portion of the section is broken away to illustrate the detonating material 3 therein. The section may take any desired shape, the shape illustrated merely being a preferred form. The outer or cover section 2 is, of course, shaped similar to the inner section and of such dimensions as to snugly cover and conform with the inner section when the container is in closed condition, as illustrated in Fig. 2.

This form of torpedo further comprises a suitable flexible strip 4 for attaching the filled container to the head of a railway track. This strip may be formed of any suitable material, such, for example, as lead. In the form of torpedo under consideration, the strip is formed in a single piece. In order to firmly attach the container to the strip, a flexible strap 5, which is preferably formed of paper, is wrapped about the strip and container. The attaching strap is preferably formed so as to conform in width with the length of the assembled container. In applying the attaching strap to the elements, the container may be placed upside down centrally upon the strap, the strip 4 placed centrally on top of the container, as illustrated in Fig. 3, and the ends of the strap wrapped about the assembled elements and attached by any suitable means, such as an adhesive. The completed torpedo with the attaching strap in operative position is illustrated in Fig. 4.

In Fig. 5, there is illustrated a modified form of torpedo, wherein container sections 1a and 2a are attached to individual attaching strips 4a and 4b by crimping the outer ends of the sections about

the strips as illustrated at 6. In this form of 5 torpedo, the sections are formed similar throughout their length with both ends open. They are preferably formed of paper as before and may take any desired shape. The outer ends of the sections are placed about the ends of strips 4a and 4b and then folded or crimped as illustrated. A suitable adhesive or any other means may be used to attach the crimped ends of the sections 10 to the strips, such adhesive being applied to the inner surface of the crimped section ends or to the strips themselves. In this instance also, the inner or receptacle section 1a is of such dimensions when attached to its associated strip that 15 it will hold the exact quantity of detonating material required for a charge.

Figs. 6 and 7 illustrate the manner in which it is contemplated to fill a plurality of containers as 20 a step in the method of manufacture of the complete torpedo. The method in question is illustrated in these figures as applied to a container of the form of torpedo illustrated in Figs. 1 to 4, but it is to be understood that the method is equally applicable to the modified form of Fig. 5. In accordance with the method as applied to the 25 torpedo of Figs. 1 to 4, after the sections of a plurality of containers have been formed, the inner or receptacle containers 1 are placed in closely adjacent position in a suitable shallow box-like tray 7. Six of the container sections are illustrated at 8 in vertical position with their open ends exposed. The remaining sections completely filling the tray are illustrated diagrammatically by means of cross lines but it will be understood 30 that it is intended that the tray be completely filled with the closely positioned sections. As shown in Fig. 7, the height of the tray is of such dimension that the upper ends of the vertically disposed sections protrude above the tray so that 35 they may be readily withdrawn therefrom after filling.

After the tray has been completely filled with the container sections, as set forth above, they are filled simultaneously with the proper quantity 45 of detonating material. This filling operation may be carried out by hand or by any suitable apparatus for automatically filling the sections. In the case of manual operation, the operator may use a scoop or trowel to spray the powdered 50 detonating material over the open end sections. After partially filling the sections simultaneously in this manner, he may pack the detonating material by jarring the tray. The filling operation may comprise successive filling and jarring until 55 all the sections are completely filled, at which time, the exact charge will be held by each of the sections.

After filling, the sections may be removed and the various torpedoes completely formed in the 60 manner set forth above. It is important to note that the detonating material when packed during the filling operation, as explained above, will not fall from the filled sections even if some of such sections should topple over in the tray during the removal thereof. Due to the successive jarrings of the tray as above set forth, the powdered detonating material becomes firmly packed, the particles adhering together. Thus the exact charge is retained by the sections at all times. 65 Obviously, tray 7 may be large enough to accommodate any desired number of container sections, the number of such sections which may be filled simultaneously being unlimited theoretically and limited only by practical considerations. If the 70 tray is made small for hand operation, it may

be provided with suitable handles (not shown) to facilitate handling by the operator especially in the jarring process. If the tray is extremely large, any suitable means for effecting the jarring thereof to pack the detonating material may be provided. As indicated above, the filling may be carried out by any suitable apparatus which functions to spray the material over the container sections after the manner of spraying by hand. Since the container sections are closely positioned, practically no detonating material is wasted and the small amount which might enter the crevices between the containers may be readily salvaged from the bottom of the tray after the removal of the filled sections. 80 85 90

In the manufacture of torpedoes of the form shown in Fig. 5, the receptacle sections of the containers may be placed upright in the tray after being completely formed with their associated strips attached. 95

It will be apparent that the method proposed herein is simple and efficient in the filling of torpedo containers which constitutes the most important and difficult step of the process of manufacturing torpedoes. Obviously, by means 100 of the method of the invention, a large number of torpedoes may be simultaneously constructed at low cost. A large saving in time and labor on the part of the operator is effected by this method.

Although specifically illustrated and described 105 herein, the invention both as to the construction of the torpedo and the novel method of making the same is not to be limited by the disclosure but is to be understood as of such scope as to include any variations or modifications as would 110 occur to persons skilled in the art and within the scope of the appended claims.

I claim:

1. A method of making track torpedoes, which comprises providing a plurality of containers of 115 such dimension that they will hold the exact quantity of detonating material required for a charge when filled and no more, placing said containers in closely assembled vertically disposed position and in juxtaposed relation to each other, 120 introducing and packing unmeasured amounts of detonating material into all of said containers simultaneously until they are filled, and sealing the filled containers.

2. A method of making track torpedoes, which 125 comprises providing a plurality of containers each comprising a pair of open end telescopic sections, the inner sections being of such dimension that they will hold the exact quantity of detonating material required for a charge when filled and 130 no more, placing the inner sections of said containers in closely assembled vertically disposed position and in juxtaposed relation to each other, introducing detonating material into all of said sections simultaneously until they are filled, and 135 telescopically applying the outer sections of said containers to the filled inner sections to seal the same.

3. A method of making track torpedoes, which comprises providing a plurality of containers of 140 such dimension that they will hold the exact quantity of detonating material required for a charge when filled and no more, placing enough of said containers in vertically disposed position and in juxtaposed contact relation to each other in a shallow box-like tray to completely fill the same, successively introducing unmeasured quantities of detonating material into all of the containers in said tray simultaneously until they are filled, jarring said tray after each introduction 145 150 155 160 165 170 175 180 185 190 195 198

of detonating material to pack the material in said containers, and removing and sealing the filled containers.	introducing detonating material into all of the container sections in said tray simultaneously until they are filled, and removing the filled sec- tions and telescopically applying the outer sec- tions thereto.	80
4. A method of making track torpedoes, which 5 comprises providing a plurality of containers each comprising a pair of open end telescopic sections, the inner sections being of such dimension that they will hold the exact quantity of detonating material required for a charge when filled and 10 no more, placing enough inner sections of said containers in vertically disposed position and in juxtaposed contact relation to each other in a shallow box-like tray to completely fill the same,	5. A track torpedo, comprising a container for holding detonating material, said container com- prising a pair only of open end telescopic sections, and a pair of flexible strips attached respectively to the sections of said container, the outer ends of said sections being crimped about the ends of said strips and secured thereto.	85
